United States Patent

Des. 242,577
Patented Nov. 30, 1976

242,577

DISPENSING CONTAINER

Thomas C. Fischer, 238 E. Westplains,
Gretna, Nebr. 68028

Filed Sept. 30, 1974, Ser. No. 510,242

Term of patent 14 years

Int. Cl. D9—99

U.S. Cl. D52—2 R

FIG. 1

FIG. 2

FIG. 3

FIG. 4

FIG. 5

FIG. 1 is a front elevational view of a dispensing container showing my new design;

FIG. 2 is a right side elevational view thereof;

FIG. 3 is a bottom plan view thereof; and

FIG. 4 is a top plan view thereof.

FIG. 5 is a bottom, front and left side perspective view thereof.

I claim:

The ornamental design for a dispensing container, substantially as shown.
